[57] CLAIM

The ornamental design for a golf shoe, as shown and described.

DESCRIPTION

FIG. 1 is a top front perspective view of a golf shoe, showing my new design;

FIG. 2 is a top plan view of FIG. 1;

FIG. 3 is a bottom view of FIG. 2;

FIG. 4 is a left side elevational view of FIG. 1;

FIG. 5 is a right side elevational view of FIG. 1;

FIG. 6 is a front elevational view of FIG. 1;

FIG. 7 is a rear elevational view of FIG. 1.

The shoe lace shown in phantom lines in FIG. 1 is for illustration purposes only and form no part of the claimed design.

The left hand shoe not shown is a mirror image of the right hand shoe disclosed in the figures.
